UNITED STATES PATENT OFFICE.

HARRY BINDER, OF BROOKLYN, NEW YORK, ASSIGNOR TO LUXOR ELECTRICAL FIXTURE CORP., OF BROOKLYN, NEW YORK, A CORPORATION OF NEW YORK.

DESIGN FOR A COMBINED STRAP AND SHIELD FOR A LIGHTING FIXTURE.

Application filed March 27, 1928. Serial No. 26,018. Term of patent 3½ years.

To all whom it may concern:

Be it known that I, HARRY BINDER, a citizen of the United States, and a resident of the borough of Brooklyn, county of Kings, city and State of New York, whose post-office address is 5521 Eleventh Avenue, in the borough of Brooklyn, county of Kings, city and State of New York, have invented a new, original and ornamental Design for a Combined Strap and Shield for a Lighting Fixture, of which the following is a specification, reference being had to the accompanying drawing, forming part thereof.

Figure 1 is a front view of the combined strap and shield, showing my design, and Figure 2 is a side view of said strap or arm.

I claim:

The ornamental design for a combined strap and shield for a lighting fixture, as shown.

HARRY BINDER.
